CLAIM

The ornamental design for a package box for pasta, as shown and described.

DESCRIPTION

1. Package box for pasta

The sole reproduction 1.0 is a perspective view. The design is a pasta package. The pasta, which can be seen on the picture of the design, forms no part of the claimed design. The broken lines in the figures illustrate the boundaries of the rectangular packaging, forming no part of the claimed design. The package box of pasta's ornamental design includes the rectangular front surface and the two dimensional image depicting a woman with red lips and a transparent dress, skirt, or other item of clothing. The transparent material of the dress or article of clothing, enabling the exposure of the contents of the pasta package is characteristic of the pasta package.
